Primary Examiner — Catherine S Posthauer*Assistant Examiner* — Joan E. Diehl(74) *Attorney, Agent, or Firm* — Cantor Colburn LLP(57) **CLAIM**

We claim, the ornamental design for a confectionery package, as shown and described.

DESCRIPTION

FIG. 1 is a perspective view of a confectionery package, showing our new design in a closed state;

FIG. 2 is a top view thereof;

FIG. 3 is a bottom view thereof;

FIG. 4 is a rear view thereof;

FIG. 5 is a front view thereof;

FIG. 6 is a side view thereof;

FIG. 7 is another side view thereof;

FIG. 8 is a perspective view of a confectionery package, showing our new design in an open state;

FIG. 9 is a top view thereof;

FIG. 10 is a bottom view thereof;

FIG. 11 is a rear view thereof;

FIG. 12 is a front view thereof;

FIG. 13 is a side view thereof; and,

FIG. 14 is another side view thereof.

The broken lines shown in the drawings are for the purpose of illustrating parts of the article that form no part of the claimed design.
